UNITED STATES PATENT OFFICE

166,854

TROPHY BASE

Donald R. Fosler and Ray Hansen, Omaha, Nebr.,
assignors to F. H. Noble & Company, Chicago,
Ill., a corporation of Illinois

Application January 15, 1952, Serial No. 18,077

Term of patent 3½ years

(Cl. D29—28)

To all whom it may concern:

Be it known that we, Donald R. Fosler and Ray Hansen, citizens of the United States, residing at Omaha, in the county of Douglas, State of Nebraska, have invented a new, original, and ornamental Design for a Trophy Base, of which the following is a specification, reference being had to the accompanying drawing, forming a part thereof, wherein:

Figure 1 is a front elevational view of the trophy base, showing our new design;

Figure 2 is a top plan view of the trophy base shown in Fig. 1;

Figure 3 is an elevational view from one side of the trophy base shown in Fig. 1;

Figure 4 is an elevational view from the other side of the trophy base shown in Fig. 1; and

Figure 5 is a rear elevational view of the trophy base shown in Fig. 1.

We claim:

The ornamental design for a trophy base, substantially as shown.

DONALD R. FOSLER.
RAY HANSEN.
